UNITED STATES PATENT OFFICE.

NICHOLAS POWER, OF BROOKLYN, NEW YORK, ASSIGNOR TO NICHOLAS POWER COMPANY, OF NEW YORK, N. Y., A CORPORATION OF DELAWARE.

SUPPORTING-FRAME FOR MOTION-PICTURE MACHINES.

1,273,921.

Specification of Letters Patent. Patented July 30, 1918.

Application filed July 14, 1914. Serial No. 850,871.

To all whom it may concern:

Be it known that I, NICHOLAS POWER, a citizen of the United States, residing in Brooklyn, county of Kings, and State of New York, (whose post-office address is #388 Jefferson avenue,) have invented new and useful Improvements in Supporting-Frames for Motion - Picture Machines, of which the following is a specification.

10 This invention relates to motion picture machines and supporting frames therefor, and has for its object to provide a moving picture machine having a frame by means of which the direction of the projection may 15 be adjusted to any desired angle relative to the level of the floor or surface on which the machine is set.

A further object of the invention is to provide a frame for moving picture machines of the class described in which the mechanism is driven by a suitable electric, or other, motor attached to the frame constructed so that the direction of the projection may be adjusted to any desired angle 25 without disturbing the level of the driving motor.

With the above objects in view my invention consists of the construction hereinafter described and illustrated in the accompanying drawings wherein,

Figure 1 is a side elevation of my improved machine, and

Fig. 2 a vertical sectional view through the supporting frame.

35 Referring to the drawings, and particularly Fig. 1, 1 represents the base of the frame which is rigidly supported at each corner on a suitable leg 2. The legs 2 are preferably made extensible by means of set 40 screws 3 in their sockets, whereby the relative lengths of the legs may be varied to maintain the base 1 level on a sloping or uneven support. Integral with the base 1 is an upwardly projecting vertical plate 4 of a 45 circular shape and having at the center of the circle a bearing or journal box 5. The upper part of the frame 6 consists of a shelf-like part 7 forming a base for the machine head 8 and having a downwardly 50 projecting vertical web 9, a portion of which

is circular in design and lies parallel to the part 4 of the base. The part 9 is supported on the base by means of a hollow spindle 10 which works in the bearing 5 and by clamping bolts 11 working in arcuate slots 55 near the periphery of the part 4. Also attached to the upper part 6 of the frame are the longitudinal rods 12 which support the lamp house 13 which incloses the arc light, or other light used to produce the projection. The rods 12 are supported at their free ends by the diagonal brace 14 mounted on the lower corner of the web 9. It will be understood that the lamp house 13 is transversely adjustable upon a pair of parallel rods 15 supported on the rods 12 as shown. The lamp house is supported on the front rod by means of the sleeve inclosing the rod while on the rear rod 15 lying under the center of the lamp house, a roller 16 is 70 provided to carry the weight of the lamp house and make the adjustment easier.

Also supported on the upper part of the frame beneath the shelf 7 is the magazine 24 which incloses the receiving reel 25 on 75 which the film is wound after its passage through the projecting machine. This reel is driven by a shaft 26 which projects through the bearing in the tubular spindle 10 and carries on its outer end a suitable 80 driving pulley belted to a driven shaft 27 of the projecting mechanism, as diagrammatically indicated in Fig. 1.

The driving motor 17 is shown as a small electric motor and it is rigidly attached to 85 the under side of the base 1 as is also the variable speed gear 18 through which the mechanism is driven by means of a belt 19 extending from the driven part of the speed gear to the driving pulley 20 of the projecting mechanism. The belt 19 does not pass directly from the gear 18 to the pulley 20 but passes over two idler rollers 21 supported on a bracket 22 consisting of a split sleeve clamped around the rod 12 and held 95 in adjusting position by means of the screw 23.

In operation the machine is set up with the base 1 leveled by means of the adjusting legs 2. The clamping screws 11 are 100

then loosened and the upper part of the frame adjusted in the bearing 5 as a center to give the desired inclination to the machine as determined by the elevation of 5 the machine above the center of the screen on which the pictures are to be projected. After adjustment the bolts 11 are set to clamp the frame parts together in a single rigid construction. The angular adjustment 10 of the frame obviously varies the distance of the pulley 20 on the driving gear thereby varying the tension of the driving belt. This difference, however, may be taken care of by adjusting the bracket 22 15 on the rod 12. Adjustment of the bracket 22 also provides for varying the path of the belt to compensate for any stretching or shrinkage of the belt. As the frame is adjusted around the reel shaft 26 as a center 20 it is obvious that the driving belt for the reel will not be affected.

For convenience of the operator in adjusting the speed gear 18 an operating handle 28 is provided pivotally mounted on 25 the front face of the upper part 6 of the frame and is provided with a locking pawl engaging the ratchet segment attached to the frame. The handle 28 is connected to the operating bell-crank 29 of the gear by 30 means of a link 30 formed of telescoping adjustable parts whereby the link may be shortened or lengthened to compensate for the adjustment of the frame.

Having thus described my invention, what 35 I claim and desire to secure by Letters Patent is:

1. In a motion picture projecting apparatus, a supporting frame comprising a stationary base portion, a driving motor mounted 40 on the base portion, an upper portion supporting the projecting mechanism, a pivotal connection between the two parts permitting relative angular adjustment, said connections comprising a hub and bearing 45 on said two parts respectively, flanges on said hub and bearing and clamping bolts for clamping said flanges together to lock said parts together in adjusted relation, and a power transmitting connection between 50 said motor and said mechanism.

2. In a motion picture projecting apparatus, a supporting frame comprising a stationary base portion, a driving motor mounted 55 on the base portion, an upper portion supporting the projecting mechanism, a pivotal connection between the two parts permitting relative angular adjustment, a power transmitting connection between said motor and said mechanism, and means for adjusting 60 said power transmitting connection to compensate for the relative adjustment of said motor and said projecting mechanism.

3. In a motion picture projecting apparatus, a supporting frame comprising a stationary base portion, a driving motor mounted 65 on the base portion, an upper portion supporting the projecting mechanism, a pivotal connection between the two parts permitting relative angular adjustment, and a power transmitting connection between said motor and said mechanism, said power transmitting connection comprising a variable speed gear supported on said base and means for adjusting said gear supported on said upper frame part and adjustably connected 70 to said gear.

4. In a motion picture apparatus, the combination of a supporting frame comprising a base, means for adjusting said base relatively to the supporting surface, an upper 80 frame part pivotally supported on said base, means for clamping said upper frame part in various positions of adjustment, a projecting mechanism mounted on said upper frame part, a receiving magazine also supported thereon, and having a reel-supporting shaft at the center of adjustment of said frame part and a driving connection between said projecting mechanism and said reel-supporting shaft.

5. In a motion picture apparatus, the combination of a frame or stand having a base, means for adjustably supporting said base at different angular positions, an upper frame part mounted on said base for angular movement in a vertical plane, said upper frame part comprising an angular frame having on its upper surface a seat for the projecting apparatus and downwardly projecting arms to embrace and support a reel inclosing magazine, and a lateral extension from said upper frame part for supporting the projecting lamp.

6. In a motion picture apparatus, the combination of a frame or stand having a base, means for adjustably supporting said base at different angular positions, an upper frame part mounted on said base for angular movement in a vertical plane, said upper frame part comprising an angular frame 100 having on its upper surface a seat for the projecting apparatus and downwardly projecting arms to embrace and support a reel inclosing magazine, a lateral extension from 110 said upper frame part for supporting the projecting lamp, and a driving motor supported on said base having driving connection with the projector on said upper frame part.

7. In a motion picture apparatus, the combination of a frame or stand having a base, an upper frame part mounted on said base for angular movement in a vertical plane, said upper frame part comprising an angu-

lar frame having on its upper surface a seat for the projecting apparatus and downwardly projecting arms to embrace and support a reel inclosing magazine and a lateral extension from said upper frame part for supporting the projecting lamp.

Signed at New York in the county of

New York and State of New York this 29th day of June, 1914.

NICHOLAS POWER.
